UNITED STATES PATENT OFFICE.

ELMER C. DITTMAR, OF WILLIAMSPORT, PENNSYLVANIA, ASSIGNOR TO THE CROOKS DITTMAR COMPANY, OF WILLIAMSPORT, PENNSYLVANIA, A CORPORATION OF PENNSYLVANIA.

BURNISHER FOR MACHINES FOR FINISHING FLOORING.

Application filed September 14, 1921. Serial No. 500,659.

To all whom it may concern:

Be it known that I, ELMER C. DITTMAR, a citizen of the United States, residing at Williamsport, in the county of Lycoming and State of Pennsylvania, have invented certain new and useful Improvements in Burnishers for Machines for Finishing Flooring, of which the following is a specification, reference being had therein to the accompanying drawing.

This invention relates to certain new and useful improvements in burnishers for burnishing the face of a finished strip of lumber in its passage through a machine for prefinishing flooring and the like as disclosed in my companion applications, the object being to provide novel means for yieldingly holding the burnisher at an angle to the face of the strip being finished.

Another and further object of the invention is to provide a burnisher in which a coil spring is employed to hold the burnishing members, the burnishing members being disposed between the convolutions of the spring in such a manner that they will be held firmly therein and in a yieldable manner so that they will engage the surface of the strip in order to burnish the face properly.

In my companion applications above referred to for prefinishing flooring, a series of glass burnishers are employed as I have found in practice that glass burnishers obtain better results than any other material and in practice these burnishers sometimes break when rigidly held or when tension is applied to the same and the object of this invention is to overcome this disadvantage as by mounting the strips of glass between the convolutions of the spring, they are held firmly and are allowed to yield so that the proper burnishing effect is obtained on the surface being treated.

Other and further objects and advantages of the invention will be hereinafter set forth and the novel features thereof defined by the appended claims.

In the drawings,

Figure 1 is a top plan view of a burnisher constructed in accordance with my invention showing the same in position in respect to the strip being burnished; and

Figure 2 is a vertical transverse section through the burnisher showing the manner

of mounting the same on an adjustable support. 55

In carrying out my invention I employ a rectangular shaped holder or box like member 1 preferably formed of metal mounted upon a member 2 formed with a vertical bore in which a spindle or pin 3 extends carried by an adjustable support 4, which enables the holder to be adjusted in respect to the material being operated on.

Arranged within the box like member 1 is a coil spring 5 held in position therein by metal strap 6 which passes through the spring and has its ends extended through suitable openings formed in the end of the box like member and bent back upon the outer wall thereof as shown at 7 so as to fasten the spring in its proper position within the box like member. 65

Disposed between the convolutions of the spring 5 are a series of glass burnishers 8 which hold the burnishers at an angle in respect to the face of the strip of material 9 being burnished as clearly shown in Figure 1 and in practice a glass burnisher is disposed between every other convolution so that the burnishers are yieldably held so as to prevent the breaking of the burnishers when pressure is applied to the same by adjusting the movable support in respect to the moving strip of lumber. 75 80 85

From the foregoing description it will be seen that I have provided a burnisher to be used in connection with burnishing strips of finished lumber composed of a coil spring having glass burnishers disposed between the convolutions thereof so as to form a yieldable support for the glass burnishers. 90

By constructing a burnisher in the particular manner shown, the glass burnishers disposed between the convolutions of the coil are held at an angle to the face of the strip being polished so that they will yield in order to prevent the breaking of the glass burnishers and I have found in practice that a burnisher constructed as shown obtains a better burnishing effect upon the finished strip of lumber as the desired pressure can be applied to the burnishers without any danger of breaking the same. 95 100 105

What I claim is:

1. A burnisher for wood finishing machines comprising a resilient member having a series of burnishers embedded therein and

means for adjustably supporting said resilient member.

2. A burnisher for wood finishing machines comprising an adjustable support, 5 a coil spring carried by said support and a series of burnishers disposed between the convolutions of said spring.

3. A burnisher for wood finishing machines comprising an adjustable support, 10 a box-like member mounted upon said support, a coil spring mounted within said box-like member and a series of burnishers disposed between the convolutions of said spring.

15 4. A burnisher for wood finishing machines comprising a coil spring having a series of glass burnishers disposed between the convolutions thereof.

5. A burnisher for wood finishing machines comprising a coil spring having a 20

glass burnisher disposed between every other convolution thereof.

6. A burnisher for wood finishing machines comprising a supporting member having a coil spring secured thereto by a strap 25 extending through said spring and a series of glass burnishers disposed between the convolutions of said spring.

7. A burnisher for wood finishing machines comprising a resilient supporting member having a rigid burnisher embedded therein.

8. A burnisher for wood finishing machines comprising a coil spring having a rigid burnisher mounted between the convolutions thereof.

In testimony whereof I hereunto affix my signature.

ELMER C. DITTMAR.
